UNITED STATES PATENT OFFICE.

JOHN PRIMROSE, OF DONGAN HILLS, NEW YORK.

STEAM-SUPERHEATER.

1,171,353.

Specification of Letters Patent.

Patented Feb. 8, 1916.

Application filed August 15, 1914. Serial No. 856,903.

To all whom it may concern:

Be it known that I, JOHN PRIMROSE, a subject of the King of Great Britain, residing at Dongan Hills, county of Richmond, State of New York, have invented certain new and useful Improvements in Steam-Superheaters, of which the following is a full, clear, and exact description.

Superheaters for steam boilers, in the form of tubes, coils or boxes, are usually combined with the boiler and furnace so as to receive heat directly from the same gases that generate the steam in the boiler. It is, however, common practice to separately fire the superheater by providing for its coils a special and independently fixed furnace, and to this latter class of apparatus the invention, subject of my present application, relates.

The temperature levels through a superheater are considerably higher than those of a steam boiler, the average temperature of the steam in the former being, under conditions that may be accepted as a basis for fair comparison, approximately 100° F. higher than that of the water in a boiler. The temperature of the waste gases on leaving the superheater would, therefore, be correspondingly higher than that of the gases leaving the boiler, besides which it is not possible to reduce the temperature by extending the heating surface or by lowering the temperature of its contents at any point, as in the case of a boiler. The efficiency, however, of all such devices depending directly upon the extent to which heat is extracted from the gases, it follows that the apparatus is the most economical and efficient which delivers to the atmosphere waste gases of lowest temperature. In this respect superheaters have of necessity been always at a disadvantage in comparison with boilers.

The primary object of my invention is to increase the efficiency of superheaters and to bring them more nearly on a par in this regard, with the forms of apparatus involving heating furnaces, and to this end the improvement consists in the combination with a separately fired superheater of a means for extracting the heat from the gases after leaving the superheater, and transferring it directly to the air which supports combustion. As a result of such improvement there is secured the effect of a regenerator by which heat is transferred

from the waste gases of the furnace before entering the chimney, directly to the fresh air which is supplied to the fire-box air chamber, and the temperature of the gases on finally leaving the superheater may be reduced to any desired point, limited only by that of the atmosphere.

The means for carrying out this invention, obviously, may vary, within wide limits, but in the accompanying drawing I have illustrated a form which is typical of the most approved arrangement known to me for the purpose.

The drawing is a view in longitudinal section of a complete plant embodying the invention.

A is a furnace, the heating chamber of which contains a superheater B of any suitable form, over the tubes of which pass the hot gases from the fire on the grate bars C. The heating chamber is extended beyond the superheater and is designed with reference thereto to provide a space intermediate the superheater and the chimney D, within which is located a series of tubes E, or any equivalents therefor, forming part of a duct or passage F carried through said chamber for conveying fresh air to the space below the grate bars. After the fire is started the draft doors G G are closed and the air for supporting combustion is drawn through the duct F F and tubes E by the chimney pull or if that is not sufficient forced through said duct by any suitable means, not shown in the drawings. In this way a large proportion of the heat of the gases after leaving the superheater is absorbed by the air passing through the tubes E and utilized for the further heating of the superheater.

I am aware that regeneration effected by raising the temperature of the air supply by heat absorbed from the waste furnace or flue gases is not new, having been applied in connection with steam boilers, blast furnaces and the like, but the specific application of the principle to separately fired superheaters, so far as I am aware, is distinctly novel, both as regards the specific means outlined above and the results accomplished thereby. I am also aware of the patent to Uhler No. 510,658 issued Dec. 12, 1893. The primary object of the three rows of tubes T, shown in the Uhler patent is to preserve the lower rows of superheater tubes from excessive heating. He specifi-

cally states, among other things, that in a group of superheater tubes the three lower rows, that is those closest to the furnace, alone can become red hot by excessive heating, and in order to protect the superheater tubes he interposes the tubes T through which cold air is adapted to enter "the furnace above the fire through nozzles U U for the purpose of consuming smoke." I find, however, that economical considerations require that the superheater be subjected to the gases immediately issuing from the furnace and thereafter extracting the remaining heat energy from said gases. In this way, and in this way only, can the maximum amount of the heat from said furnace gases be utilized.

What I claim is:—

The combination with a furnace having a passage or chamber for connecting the fire box and chimney, of a superheater located in said passage and adapted to receive the gases immediately issuing from the fire-box, and a duct for conveying air to the fire extending through a chamber in said furnace and located between the superheater and the chimney whereby the heat of the gases after leaving the superheater will be transferred directly to the air which supports combustion. 25

JOHN PRIMROSE.
